UNITED STATES PATENT OFFICE.

PATRIK L. PETERSON, OF NORTH GROSVENOR DALE, CONNECTICUT,
ASSIGNOR TO DRAPER COMPANY, OF HOPEDALE, MASSACHU-
SETTS, A CORPORATION OF MAINE.

BACK-STOP FOR PICKER-STICKS.

No. 832,025.

Specification of Letters Patent.

Patented Sept. 25, 1906.

Application filed December 4, 1905. Serial No. 290,067.

To all whom it may concern:

Be it known that I, PATRIK L. PETERSON, a citizen of the United States, and a resident of North Grosvenor Dale, county of Windham, State of Connecticut, have invented an Improvement in Back-Stops for Picker-Sticks, of which the following description, in connection with the accompanying drawings, is a specification, like numerals on the drawings representing like parts.

This invention has for its object the production of a novel back-stop or positioning device to coöperate with a loom picker-stick on its outward stroke and stop the same at the desired point.

The back-stop is adjustably mounted on the lay to take up wear when necessary and also to regulate the stopping and starting point of the picker-stick.

2 The various novel features of my invention will be fully described in the subjoined specification and particularly pointed out in the following claims.

Figure 1 is a front elevation, partly broken out, of one end of a loom-lay and the adjacent picker-stick with one embodiment of my invention in operative position. Fig. 2 is a rear elevation of the lay, showing the means by which the back-stop is adjustably secured in position; and Fig. 3 is a perspective view of the back-stop detached.

The lay 1, longitudinally slotted at 2 in usual manner for the swinging picker-stick 3, the binder 4, cover-plate 5, and front box-plate 6, Figs. 1 and 2, may be and are all of usual or well-known construction, the part 7 of the lay forming the outer end of the slot 2, being cut away, as at 7^x, Fig. 1.

Various devices have been provided to stop the picker-stick at the outer end of the lay, such devices being more or less efficient and convenient and depending on springs, spring-controlled stops or pneumatic devices for their operation.

45 In my present invention I have provided a back-stop which has great simplicity and strength of construction and which is secured in an adjustable manner on the lay, so that the stopping-point of the picker-stick can be 50 regulated as desired and wear taken up, the use of springs or spring-controlled devices and

pneumatic stops or cushions being wholly obviated.

Referring to Fig. 3, a flat elongated stand 8 is dropped at its outer end at 9 and continued as a lateral arm 10 at right angles to the stand, the outer end of the arm being enlarged to form a heavy and rigid back-stop 11, having a convex face 12, recessed at top and bottom at 13. A piece of leather, rubber, raw-hide, or other suitable material, as 14, is sprung into the recesses over the face 12 of the back-stop to provide the impact face or surface against which the picker-stick strikes at the desired point of stoppage on its outward stroke. I form a guideway on the rear side of the lay by means of two parallel longitudinal ribs 15 (see Fig. 2) adjacent the end of the lay, the guideway being wide enough to permit the stand 8 to be slidably seated therein, the arm 10 extending across the lay below the end portion 7 of the slot 2, the drop 9 permitting the arm to do so. The arm 10 is of such length that the back-stop is laterally offset from the stand in the path of the picker-stick on its outward stroke, as will be manifest, the convex portion of the back-stop or, rather, the impact member 14 taking the blow of the picker-stick. A slot 16 in the stand receives a bolt 17, Fig. 2, extended through the rear portion of the lay, a nut 18 on the bolt clamping the stand firmly in position on the lay. By loosening the nut the back-stop can be adjusted inward or outward, as necessary, the guideway sustaining the stand and preventing any displacement thereof or of the back-stop, and after the nut 18 is set up the device is rigidly secured in the desired position on the lay. The stand, arm, and back-stop are conveniently made as an integral piece by casting or forging, and when the impact member 14 becomes too much worn it can be removed and a new one readily inserted, the position of the recesses 13 holding it in place without other fastening.

The device is cheap, strong, and durable, it is adjusted and clamped in place by a single clamping member, and forms an effective stop for the picker-stick.

Having fully described my invention, what I claim as new, and desire to secure by Letters Patent, is —

1. A lay longitudinally slotted for the picker-stick, parallel longitudinal guide-ribs on the rear side of the lay near its outer end, a back-stop having convex, face in the path of 5 and to stop the picker-stick on its outward stroke, a non-metallic facing detachably secured to the back-stop and lying against the convex face thereof, a stand rigidly connected with and laterally offset from the 10 back-stop and slidably mounted between the guide-ribs, and adjustable means to clamp the stand to the lay and thereby position the back-stop.
2. A lay longitudinally slotted for the 15 picker-stick and having a longitudinal guideway near the outer end, a slotted stand slidably seated in the guideway, a clamping-bolt to secure it in adjusted position, a rigidly-attached metallic back-stop laterally offset 20 from said stand and positioned in the path of

and to stop the outward stroke of the picker-stick, and a renewable leather facing to cover the face of the back-stop.

3. A lay longitudinally slotted for the picker-stick, a metallic back-stop in the path 25 of the picker-stick on its outward stroke, said back-stop having a convex face and transverse, parallel retaining-recesses at the upper and lower ends thereof, a leather impact member removably held in place by said recesses, covering and resting against the convex face of the back-stop, and means to adjustably attach the back-stop to the lay.

In testimony whereof I have signed my name to this specification in the presence of 35 two subscribing witnesses.

PATRIK L. PETERSON.

Witnesses:

JOHN G. GRONLUND,
FRANK S. RICHMOND

It is hereby certified that in Letters Patent No. 832,025, granted September 25, 1906, upon the application of Patrik L. Peterson, of North Grosvenor Dale, Connecticut, for an improvement in "Back-Stops for Picker-Sticks," errors appear in the printed specification requiring correction, as follows: On page 2, line 4, after the word "having," the article *a* should be inserted, and same line, same page, the comma after the word "convex" should be stricken out; and that the said Letters Patent should be read with these corrections therein that the same may conform to the record of the case in the Patent Office.

Signed and sealed this 16th day of October, A. D., 1906.
